TOASTER END PANEL WITH CORD STORAGE

Berton R. Oxel, Louisville, Ohio, assignor to The Hoover Company, North Canton, Ohio

Filed June 23, 1972, Ser. No. 265,824

Term of patent 14 years

Int. Cl. D7—02

U.S. Cl. D7—93

FIG. 1

FIG. 2

FIG. 3

FIG. 4

FIG. 1 is a perspective view of a toaster end panel with cord storage showing my new design, the broken line showing of the toaster housing and cord being for purposes of illustrating an environment in which the design may be used;

FIG. 2 is an end elevational view;

FIG. 3 is a side elevational view thereof, and

FIG. 4 is a bottom plan view.

I claim:

The ornamental design for a toaster end panel with cord storage, substantially as shown and described.
